UNITED STATES PATENT OFFICE.

CLEVELAND CHRISTIAN SHELTON, OF BUCKNER, VIRGINIA.

BROOM HOLDER.

1,414,049.

Specification of Letters Patent. Patented Apr. 25, 1922.

Application filed September 21, 1921. Serial No. 502,195.

To all whom it may concern:

Be it known that I, CLEVELAND CHRISTIAN SHELTON, a citizen of the United States, residing at Buckner, in the county of Louisa,

5 State of Virginia, have invented a new and useful Broom Holder; and I do hereby declare the following to be a full, clear, and exact description of the invention, such as will enable others skilled in the art to which

10 it appertains to make and use the same.

The invention relates to broom holders and has for its object to provide a device of this character which may be easily attached to a wall or the like and supported in a horizontal plane for holding a plurality of brooms in such a manner that said brooms may be easily and quickly removed for vending.

A further object is to provide a broom holder formed from a pair of hingedly connected arms, said arms being connected together adjacent their hinged points by coiled springs, which coiled springs normally hold inwardly extending semi-circular ends of 25 the hinged members in engagement with each other. Also to form one of said members and a supporting arm carried thereby from a single piece of metal, said metal being twisted at its rear end to form a right angularly disposed arm adapted to be attached to a wall, and also to form spaced flanges between which flanges the inner end of the other hinged arm is pivoted.

With the above and other objects in view 35 the invention resides in the combination and arrangement of parts as hereinafter set forth, shown in the drawings, described and claimed, it being understood that changes in the precise embodiment of the invention 40 may be made within the scope of what is claimed without departing from the spirit of the invention.

In the drawings:—

Figure 1 is a perspective view of the 45 holder.

Figure 2 of the inside of one of the hinged members, which member has formed integral therewith a wall engaging arm.

Figure 3 is a top plan view of the rear end 50 of the holder, showing parts in section to better illustrate the structure.

Referring to the drawings, the numeral 1 designates a broom holder, which holder comprises spaced bars in parallel relation to 55 each other, said bars being designated by the numerals 2 and 3. The outer ends of the

bars 2 and 3 are provided with inwardly extending semi-circular portions 4, which portions are normally held in engagement with each other by means of a coiled spring 5 in 60 such a manner that broom handles may be forced between the portion 4 against the action of the spring 5. The members 2 and 3 adjacent their rearward end are bent inwardly as at 6 and are pivotally connected together at 7, thereby forming a pivotal point on which the member or bar 3 may pivot outwardly in a broom receiving or removing operation. When a broom is removed by pulling the same outwardly, it will be seen that 70 the broom handle 8 will force the bar 3 outwardly against the action of the spring 5; however the other brooms being supported will be held in the holder.

The bar 2 is preferably formed from a 75 piece of strap iron bent upon itself centrally to form the channel 2^a between the flanges of which the lug 9 of the bar 3 is pivoted, which lug extends through an aperture 10 in the bottom of the channel 2^a, said flanges 80 forming means for bracing the arm and securely holding the same against wobbling incident to constant use. The bar 2 at a point beyond the pivotal point 7 is twisted at 11 thereby forming an upwardly extending right angularly disposed arm 2^b, which arm is provided with apertures 2^c through which screws may be passed for securing the broom holder as a whole to a wall or support. 85

From the above it will be seen that a 90 broom holder is provided which is simple in construction and one which may be easily and quickly applied to a wall or support. The hinged bar 3 may be also formed from a single piece of strap iron and between the 95 flanges 3^a thereof and the flanges 2^b of the bar 2 the ends of the coiled spring 5 may be secured on pins 12.

The invention having been set forth what is claimed as new and useful is:—

1. A broom holder comprising hingedly connected horizontally disposed bars, the free ends of said bars being provided with inwardly extending members for engaging each other and limiting the inward movement of the free ends of the bars, a coiled spring disposed between said bars and having its ends connected to the bars adjacent their hinging points and an upwardly extending integral arm carried by one of said 105 bars and forming means whereby the holder as a whole may be attached to a support. 110

2. A broom holder comprising a pair of spaced bars, the outer ends of said bars being provided with inwardly extending semi-circular portions horizontally disposed and adapted to engage each other and limit the inward movement of the bars, the rear ends of said bars curving inwardly towards each other and pivotally connected together, one of said bars being formed from a strip of metal bent to form inwardly extending horizontally disposed flanges, said last named bar being bent at a point beyond the pivotal points between the bars at a right angle, thereby forming a supporting arm adapted to be attached to a support, the other bar being formed from a single strip of material

bent upon itself to form horizontally disposed flanges and a lug adapted to be received between the flanges of the other bar and to be pivoted therebetween for forming the hinging point between the bars, a coiled spring disposed between said bars and means whereby said coiled spring may have its ends secured between the flanges of the hinged bars. 20

In testimony whereof I have signed my name to this specification in the presence of two subscribing witnesses.

CLEVELAND CHRISTIAN SHELTON.
